CLAIM

The ornamental design for a portable cordless neck massager, as shown.

DESCRIPTION

FIG. 1 is a rear elevational view of a portable cordless neck massager showing our new design;

FIG. 2 is a front elevational view thereof;

FIG. 3 is a bottom plan view thereof;

FIG. 4 is an end elevational view as seen along line 4—4 in FIG. 1;

FIG. 5 is an end elevational view as seen along line 5—5 in FIG. 1; and,

FIG. 6 is a reduced perspective view in an alternate position.
